UNITED STATES PATENT OFFICE.

JOSEPH JOHN NELIS, OF BROOKLYN, NEW YORK, ASSIGNOR TO POWER SPECIALTY COMPANY, OF NEW YORK, N. Y., A CORPORATION OF NEW YORK.

SUPERHEATER.

Application filed January 24, 1921. Serial No. 439,381.

To all whom it may concern:

Be it known that I, JOSEPH J. NELIS, a citizen of the United States, residing at New York city, borough of Brooklyn, in the county of Kings and State of New York, have invented certain new and useful Improvements in Superheaters, of which the following is a full, clear, and exact description.

10 The invention forming the subject of my present application for Letters Patent is an improvement pertaining to steam boilers of the inclined tube type with two tube banks and with two lower drums and one top drum 15 and similar to and for convenience herein-after referred to as the Yarrow type, and such improvement involves primarily the combination with these boilers of superheaters in such manner and in such form as to 20 secure a new and highly useful result. Secondly, the said improvement resides in the combination with such boilers, when equipped with superheaters in the novel manner devised by me of certain baffles which contribute to the efficiency of the boiler.

Superheaters have been for many years used with boilers of the Yarrow type, by placing them in spaces in the partly vertical banks of tubes formed by dividing such 30 banks sufficiently for the purpose, and baffles of varying character and in many positions have been used therewith for directing the flow of hot gases over the tubes of the boiler and the superheaters, but I have found that 35 the use of a special form of superheater with these boilers secures great and important advantages by the greater efficiency which results from its use, and, finally, I have by the use of baffles in certain new relations added 40 to the efficiency of the boiler in its operation. These several improvements may be first generally described and then more specifically pointed out and claimed.

The superheaters commonly used with 45 Yarrow boilers heretofore have been of the ordinary or plain tube type. Such superheaters, unless specially made with small tubes placed very close together, which is highly objectionable by reason of the high 50 velocity of the steam which such construction involves, do not have any substantial baffling effect, as the hot gases flow with but little resistance between the tubes and are not materially deflected from their natural 55 course thereby. I propose, however, to use

a superheater of a character which constitutes a leaky baffle. That is to say, I use a Foster superheater, the tubes of which are encased in cast iron rings which form corrugated envelopes, and which constitute virtually a baffle; that is, a leaky baffle without rendering it necessary to reduce the diameter or capacity of the tubes.

By placing such superheaters in the two banks of the boiler and using superheaters 60 of proper proportions and dimensions, I secure throughout any desired portion of each bank a leaky baffle which causes a large proportion of the hot gases to flow upward over that part of the bank which is nearest the 65 fire and downward over the outside portion being directed through this course by the usual baffles outside the banks of tubes. Of course, the entire volume of gas will not thus flow as a part will pass or leak through 70 between the superheater tubes. Such gases as thus pass the superheater would manifestly flow immediately across the lower portion of the outside tubes unless restrained, and for this purpose I arrange back of each 75 superheater a solid baffle of proper dimensions, which causes all of the leaking gases to flow upward, unite with the gases deflected upward by the superheater and thence 80 downward over the outside tubes.

In boilers of this kind it is especially difficult to remove a section or U-tube from the cluster constituting the superheater, but this I remedy by bending the ends of each tube section outwardly so as to join the header in 85 a plane at right angles to the legs of the section, so that when any section has to be removed, it is merely necessary to cut the tube near the header and withdraw the section bodily without interfering with the 90 headers. The ends of a new section when introduced need only be pinched together to clear the headers and register with the openings therein.

In the accompanying drawings I have 100 shown these improvements in detail.

Figure 1 is a view in elevation of the interior of a Yarrow boiler, with my improvements embodied therein.

Fig. 2 is a sectional view on line 2-2 of 105 Fig. 1, of the superheater showing my improvement in means for facilitating the removal or withdrawal of a section, and

Fig. 3 is a top plan view of the same parts.

Boilers of the type contemplated in this 110

case have two inclined banks of tubes 1 and 2, with drums 3, 3, below to which they are connected and a main central steam drum at the top. Each bank is divided longitudinally and superheaters 5 are located in the spaces thus formed. To cause the hot gases to flow over the outside tubes baffles 8 are commonly used over the outside upper portion and outside of each bank of tubes.

10 The construction of the superheater which I use is shown in Fig. 2. It consists of a series of U-tubes 7, encased in corrugated cast iron rings 6, which fill up the spaces between the tubes to a sufficient extent to 15 constitute a leaky baffle. The superheaters occupy most of the spaces in the banks of tubes and deflect a large proportion of the hot gases upward as indicated by the arrows, so that such gases sweep both the inner and the outer sections of each bank.

A portion of the gases also passes between the superheater tubes, as indicated, and prevent these gases from flowing immediately across the lower portion of the outside tubes 25 only, I place baffles 13 back of the superheaters and between the boiler tubes which force such leaking gases to pass upward and then down over substantially the entire length of the outside tubes.

30 The ends of the U-tubes constituting the superheaters are bent outwardly at right angles, as shown in Fig. 2. The tubes pass through removable plates 9 into a closed compartment 10 outside the boiler and are 35 expanded, in the usual manner, into the headers 11. Wherever it becomes necessary to remove one of these tubes it is cut near the headers and it may then be lifted out without disturbing the headers. The latter are 40 provided with openings closed by caps 12 which may be removed to withdraw the cut ends of the tubes, and to permit new ends to be expanded into the headers.

When a new section is introduced the ends 45 of the tube are pinched or forced together, which permits them to be passed down into register with the openings in the headers in which they are expanded.

In constructing the superheaters for use, 50 as above set forth, the dimensions of the cast iron rings which form the envelopes for the superheater tubes are determined largely without reference to the diameter of the heating tubes, so as to oppose the flow of 55 gases between the said tubes to a sufficient extent to give to the superheater, as a whole,

the effect of a leaky baffle. The efficiency of the boiler may, in this way, be materially increased, especially when the other provisions hereinbefore set forth are made. 60

What I claim is:—

1. In a boiler of the Yarrow type, the combination with the banks of boiler tubes longitudinally divided to form spaces, and baffles outside of the upper parts of said 65 tubes, of superheaters constituting leaky baffles arranged in said spaces, and baffles back of said superheaters for deflecting such gases as pass through the superheaters and causing them to flow upward and unite 70 with the gases deflected by the superheaters and flow downward over the outside boiler tubes.

2. In a boiler of the Yarrow type, the combination with the banks of boiler tubes 75 longitudinally divided to form spaces, of superheaters constituting leaky baffles, arranged in said spaces and baffles back of said superheaters for deflecting such gases as pass through the superheaters and causing 80 them to flow upward and unite with the gases deflected by the superheaters.

3. In a boiler of the Yarrow type, the combination with banks of boiler tubes longitudinally divided to form spaces, of 85 superheaters in said spaces having their tubes encased in corrugated cast-iron envelopes which close up the spaces through the superheater so as to form a leaky baffle and operate to deflect a large portion of the 90 hot gases around them and over the boiler tubes, and ordinary baffles back of said superheater and beyond a row of boiler tubes for deflecting such hot gases as pass through the superheater and causing them to flow upwardly sweeping the boiler tubes and unite 95 with the gases deflected by the superheater.

4. In a boiler of the Yarrow type, the combination with the banks of boiler tubes longitudinally divided to form spaces, of 100 superheaters constituting leaky baffles arranged in said spaces, and baffles back of said superheaters and back of a row of boiler tubes for deflecting such hot gases as pass through the superheater and causing 105 the same to sweep upwardly above the boiler tubes and unite with the hot gases deflected by the superheaters.

In testimony whereof I hereunto affix my signature.

JOSEPH JOHN NELIS.
